VULCANIZER

Application filed April 28, 1928. Serial No. 273,684.

This invention relates to vulcanizers comprising relatively movable mating vulcanizer sections.

Heretofore, it has been proposed to provide a vulcanizer with relatively movable mold mating sections electromagnetically closed and held together during a curing operation. Such devices have, however, not been commercially feasible because of certain disadvantages, among which are occasional failure of the electrical power, permitting the vulcanizing sections to separate before a cure is completed, improper seating of the mold sections carried by the vulcanizer sections, and the liability of injury to workmen by being caught between the vulcanizer sections by premature operation of the electromagnets.

The purpose of the present invention is to provide an improved electromagnetically operated vulcanizer which is so designed as to overcome the foregoing disadvantages and to be capable of simple, highly efficient operation in the vulcanization of tire casings, inner tubes and other rubber articles.

This application is a continuation in part of application Serial No. 111,782, filed May 26, 1926.

The objects of the invention are attained in the various vulcanizer constructions disclosed in the accompanying drawings and briefly described below. It is to be understood that the invention is not limited to the specific form thereof shown and described.

35 Of the accompanying drawings,

Figure 1 is a side elevation of a vulcanizer embodying the invention;

Figure 2 is a front elevation thereof;

Figure 3 is a section on line 3-3 of Figure 2;

Figure 4 is an enlarged detail section of the left portion of Figure 3;

Figure 5 is an elevation of the vulcanizer control device;

Figure 6 is a section through the control device;

Figure 7 is a detail diametral section of a portion of a modified form of vulcanizer embodying the invention;

50 Figure 8 is a side elevation of another

form of vulcanizer embodying the invention;

Figure 9 is a front elevation thereof;

Figure 10 is a diagrammatic plan of a vulcanizer control switch and wiring; and

55

Figure 11 is a side elevation thereof.

Referring to the drawings, the numeral 10 represents a suitable standard having mounted thereon a vulcanizer comprising mating sections 11 and 12, the latter hinged 60 for movement toward and from the former on hinges 13, 13.

Section 11 carries an inner tube mold section 14 and section 12 an inner tube mold section 15 arranged to mate with each other and 65 having cavities for circulation of a curing medium as shown at 14^a and 15^a.

Vulcanizer section 11 is provided with electromagnets 20 and 21 about the outer and inner peripheries of mold section 14, these 70 magnets being housed in circumferential grooves 18 and 19 in section 11 and retained therein by plates 22 and 23. In order to secure proper seating of mold members 14 and 15 under pressure on each other by magnetic 75 actuation of the vulcanizer sections, the mold sections are adjustable by screws 16 so that when sections 14 and 15 mate at 17, there is slight clearance between the faces of the vulcanizer sections as indicated at 17^a.

80

A simple, effective and safe control device for operation of this type of vulcanizer comprises a rock shaft 25 journaled on stationary vulcanizer section 11 and operable by a vulcanizer locking lever 26 which carries a cam lug 27 for engaging a cam lug 28 on the outer side of the vulcanizer section 12 after the vulcanizer sections have been moved into juxtaposition ready for curing an enclosed tube in the mold. Shaft 25 carries switch members 29, 29 for establishing a circuit through the electromagnets when the lever 26 is swung to locking position as shown, connecting the magnets to power lines 30, 30 as will appear from the diagrammatic wiring in Figure 4. 85 Rock shaft 25 also carries a mold "breaking" or mold "cracking" cam lug 31 engaging a cam lug 32 on the vulcanizer section 12 to slightly separate the vulcanizer sections as the locking cams 27 and 28 are released by 100

swinging lever 26 away from the locking position shown in the drawings.

To prevent actuation of the lever 26 while the vulcanizer sections are apart, section 11 is provided with a spring pressed plunger 33 in a socket therein normally urged outwardly from the face of the vulcanizer and engaging in back of a shoulder 34 on cam 31, this plunger being compressible out of engagement with the shoulder 34 by the face of section 12 when the sections are closed to permit actuation of rock shaft 25 by lever 26.

In Figure 7 there are shown several features which may be employed in vulcanizers of this type which will be of particular advantage for certain purposes. A different mode of securing relative adjustment of mold and vulcanizer sections is shown. The mold sections 40 and 41 are secured to vulcanizer sections 42 and 43, the mold section 40 being adjustable on vulcanizer section 42 by screws 44 and 45.

Electromagnets 46, 47, 48 and 49 are provided opposite each other in the vulcanizer sections whereby by energizing the magnets in the same direction, they will draw the sections together, and by reversely energizing the magnets, they will urge the sections apart. This feature may be employed instead of or additional to the breaking cam lug 31 on rock shaft 25.

In order to compensate for misalignment of the vulcanizer sections when swung into mating relationship and magnetically locked, such as would be caused by improper hinge action of the sections, one of the sections, such as 41, may be carried on a flexible plate 46 capable of being flexed under the strong magnetic action to render vulcanizer section 43 self-adjusting.

Figures 8 and 9 illustrate a safety latch 50 for securing together magnetically actuated vulcanizer sections 51 and 52, the latch being pivoted on section 51 and arranged to engage a lug 53 on section 52 and being adapted to be released electrically by actuation of a solenoid control device 54. A suitable control switch for a vulcanizer equipped with opposed electromagnets and the electrically controlled latch is shown in Figures 9 and 10. A double throw switch 55 is arranged to energize magnets 46 and 48 and 47 and 49 in the same direction in one position (the full line position shown) and to reversely energize magnets 46 and 48 and 47 and 49 in the other position thereof, said switch being arranged to first engage contacts 54a by establishing a circuit to solenoid 54 as the switch is swung to vulcanizer opening position (dotted line position) whereby latch 50 will be released before the electromagnets are energized to repel each other to open the vulcanizer.

The simple, effective manner for operating and controlling the operation of the various vulcanizers shown will be apparent

from the preceding description. Modifications other than those disclosed herein may be resorted to without departing from the spirit of the invention or the scope of the appended claims.

What is claimed is:—

1. The combination with relatively movable vulcanizer sections and electromagnetic means for holding said sections together, of mating mold sections carried by said vulcanizer sections, said sections being adjustable relative to the vulcanizer sections to positions so as positively to seat upon each other with the vulcanizer sections having slight clearance between the faces thereof.

2. The combination with relatively movable vulcanizer sections and electromagnetic means for holding the sections together, of means for latching the sections together, and a switch actuatable by engagement of said latching means to energize the electromagnetic means.

3. The combination with relatively movable vulcanizer sections and electromagnetic means for holding said sections together, of means operable in one direction for locking the sections together and in another direction to crack the sections, and a switch actuatable by said vulcanizer locking or cracking means for energizing the electromagnets when the locking device is engaged and for de-energizing the electromagnets as the locking device is disengaged and the sections cracked.

4. The combination with relatively movable vulcanizer sections and electromagnetic means for holding the sections together, of a locking device for holding the sections together, a switch actuatable by engagement of the locking device to energize the electromagnets, and means operable when the vulcanizer is open to prevent actuation of the locking device, said means comprising a spring pressed plunger in the face of one vulcanizer section normally projecting therefrom and a shoulder on the locking device with which said plunger engages, the plunger being compressible by the face of the other vulcanizer section out of engagement with said shoulder.

5. The combination with relatively movable vulcanizer sections and electromagnetic means for holding the same together during a curing operation, of means for energizing the electromagnetic means, said energizing means being locked against actuation until the vulcanizer sections are moved together.

6. The combination with relatively movable vulcanizer sections and electromagnetic means for holding the same together during a vulcanizing operation, of a locking device for holding the sections together, means actuated by engagement of the locking device for energizing the electromagnetic means, a vulcanizer cracking device operable by disen-

gagement of the locking device comprising a cam lug engageable with one vulcanizer section, said cam lug having a shoulder thereon, and means engageable with said shoulder 5 when the vulcanizer is open to prevent actuation of the locking device and energization of the electromagnetic means.

7. The combination with a vulcanizer comprising relatively movable sections and electromagnetic means for holding said sections together, of a vulcanizer cracking means, and means for energizing the electromagnetic means, said means being adapted to be locked against actuation when the vulcanizer is 15 open by said vulcanizer cracking means.

8. The combination with hinged vulcanizer sections movable to and from mating relationship and electromagnetic means for holding the sections together, of means for locking the mold sections together, for energizing or de-energizing the electromagnetic means and for cracking the mold sections comprising a rock shaft having a locking cam lug thereon, a cracking cam lug thereon and a switch 25 thereon so as to be rocked in one direction to lock the sections and energize the electromagnetic means and to be rocked in the other direction to de-energize the magnetic means and crack the vulcanizer, and means for locking said rock shaft against actuation to energize the electromagnetic means when the vulcanizer is open.

9. The combination with hinged vulcanizer sections movable to and from mating relationship and electromagnetic means for holding the sections together, of means for locking the mold sections together, for energizing or de-energizing the electromagnetic means and for cracking the mold sections comprising a 30 rock shaft having a locking cam lug thereon, a cracking cam lug thereon and a switch thereon so as to be rocked in one direction to lock the sections and energize the electromagnetic means and to be rocked in the other direction to de-energize the magnetic means and crack the vulcanizer.

10. The combination with hinged vulcanizer sections movable to and from mating relationship and electromagnetic means for holding the sections together, of means for locking the mold sections together and for energizing or de-energizing the electromagnetic means comprising a rock shaft having a locking cam lug thereon and a switch thereon so as to be rocked in one direction to lock the sections and energize the electromagnetic means and to be rocked in the other direction to de-energize the magnetic means, and means for locking said rock shaft against actuation 55 to energize the electromagnetic means when the vulcanizer is open.

11. The combination with hinged vulcanizer sections movable to and from mating relationship and electromagnetic means for holding the sections together, of means for 60

locking the mold sections together and for energizing or de-energizing the electromagnetic means comprising a rock shaft having a locking cam lug thereon and a switch thereon so as to be rocked in one direction to lock the sections and energize the electromagnetic means and to be rocked in the other direction to de-energize the magnetic means.

12. The combination with relatively movable vulcanizer sections and electromagnetic means for holding the sections together, of a locking device for holding the sections together, a switch actuatable by engagement of the locking device to energize the electromagnetic means, and means operable when the vulcanizer is open to prevent actuation of the locking device.

13. A vulcanizer comprising hinged sections movable to and from mating relationship, and electromagnetic means for holding said sections together, one of said sections being mounted on a flexible element connected to one hinge member whereby the said section will adjust itself under the magnetic force to compensate for any misalignment of the vulcanizer sections.

14. A vulcanizer comprising relatively movable vulcanizer sections, electromagnetic means for urging the sections together or apart, and means for locking the sections together to prevent separation thereof due to failure of the electromagnetic means.
